UNITED STATES PATENT OFFICE

WINIFRED L. GIBBONS, OF PROVIDENCE, RHODE ISLAND, ASSIGNOR TO C. G. KING & CO., INC., OF PROVIDENCE, RHODE ISLAND

DESIGN FOR A CAMPAIGN PIN

Application filed February 23, 1932. Serial No. 42,969. Term of patent 7 years.

To all whom it may concern:

Be it known that I, WINIFRED L. GIBBONS, a citizen of the United States, residing at Providence, in the county of Providence and State of Rhode Island, have invented a new, original, and ornamental Design for a Campaign Pin, of which the following is a specification, reference being had to the accompanying drawings, forming part thereof.

In said drawings, Fig. 1 is a front face view, and Fig. 2 is an edge view of a campaign pin, showing my new design.

I claim:

The ornamental design for a campaign pin as shown.

Signed at Providence, in the county of Providence and State of Rhode Island this 19th day of February A. D. 1932.

WINIFRED L. GIBBONS.
